(57) **CLAIM**

The ornamental design for a hand tool, as shown and
described.

DESCRIPTION

FIG. 1 is a top perspective view of a hand tool;
FIG. 2 is a top plan view of the hand tool shown in FIG. 1;
FIG. 3 is a top plan view of the hand tool, depicted with a
removable central segment removed from a handle of the
hand tool;

FIG. 4 is a top plan, exploded view thereof;

FIG. 5 is a left-side elevational view thereof;

FIG. 6 is a rear elevational view thereof; and,

FIG. 7 is a front elevational view thereof.

The ornamental design which is claimed is shown in solid
lines in the drawings. The broken lines in the drawings form
no part of the claimed design. A bottom plan view is not
shown because it is identical to the top plan view shown in
FIG. 2. A right-side elevational view is not shown because
it is a mirror image to the left-side elevational view shown
in FIG. 5.
